SOLE FITTING MACHINE

Lawrence Mawbey, Leicester, England, assignor
to United Shoe Machinery Corporation, Flem-
ington, N. J., a corporation of New Jersey

Application June 20, 1947, Serial No. 755,861
In Great Britain July 13, 1946

7 Claims. (Cl. 12—27)

1

This invention relates to sole fitting machines and is herein illustrated and described as embodied in a channeling machine of the type disclosed in United States Letters Patent No. 1,023,801, granted April 23, 1912 upon the application of Frederic E. Bertrand. Such a machine is used to cut a pair of channels in an insole, the resulting channel lips being raised back-to-back to form a sewing rib. To reduce considerably the tendency of the raised channel lips to return to their original positions, it is customary to make transverse slashes in one or both lips or in the sole material from which the lips are to be cut. To avoid unduly weakening the sewing ribs, these slashes should be spaced apart a distance considerably greater than the length of the feed stroke of the machine. Channeling machines equipped to form such slashes are, therefore, usually arranged to permit the machine to make several feeding strokes for each slash. However, channeling machines of this type are provided also with mechanism for enabling the length of the feed stroke to be shortened when going around the toe portion of the sole, thereby necessitating some further provision for preventing the slashes from being brought too close together at that portion.

The channeling machine disclosed in Letters Patent No. 2,242,415, granted May 20, 1941 upon the application of William N. Bray and Charles M. Bagshaw is equipped with an arrangement for forming slashes in the lip in proportion to the number of feed strokes of the machine, and also with means for increasing this ratio, that is, requiring a greater number of feed strokes to each slashing stroke, when the feed stroke is shortened. The slashing mechanism of this patented machine is operated by a cam driven in synchronism with the main shaft of the machine. A counting device in the form of an adjustable ratchet mechanism determines the number of cycles required before an operating stroke of the slashing mechanism can take place, this counting mechanism being automatically adjustable to render the required number of cycles greater when the feed stroke is shortened.

It is an object of the present invention to provide, in a channeling machine of the type under consideration, a slashing device which is more rugged in construction and more definite with regard to the ratio of the slashing strokes to the feed strokes of the machine than any prior slashing device. In accordance with this object, the illustrated machine is provided with at least two alternative knife operation controlling

2

mechanisms having different characteristics and capable of being selectively rendered operable to cause the operation of the knife to be controlled as desired. In the illustrated machine each of these controlling mechanisms is constructed and arranged to cause a slashing knife to be operated periodically in timed relation to the operating cycles of the machine at a ratio between the operating cycles of the machine and the operations of the knife which is different from the operating ratio of the other mechanism, and either mechanism may be selectively rendered operative to cause the knife to be operated at the desired ratio. As shown herein, these mechanisms comprise driven cams of different characteristics and means for selectively engaging a cam follower with either of these cams.

The term "operating cycle of the machine," as used herein, refers to one of a series of operations which are repeated during the channeling of a work piece such as a sole. For example, in a machine employing oscillating channeling knives such as the one illustrated herein, an operating cycle would be the movement of a channeling knife from the time it starts on a cutting stroke until it is ready to start on the next cutting stroke. In a machine where the channeling knives are stationary and the work is forced past the knives by feeding means, such as an oscillating feed foot, one complete to-and-fro movement of such means would be an operating cycle.

These and other features of the invention, including certain details of construction and combinations of parts, will be shown as embodied in an illustrative machine and will be pointed out in the appended claims.

Referring to the accompanying drawings.

Fig. 1 is a front elevation of a head of an illustrative channeling machine embodying the invention;

Fig. 2 is an angular view of the machine head shown in Fig. 1;

Fig. 3 is a sectional view taken on the line III—III of Fig. 1;

Fig. 4 is a detail in side elevation of a cam controlling mechanism;

Fig. 5 is a detail in front elevation of the slashing knives and their carrier;

Fig. 6 is a detail in front elevation of a portion of the controlling mechanism;

Fig. 7 is a detail in side elevation of the channeling knives and the slashing knives together with their carriers;

Fig. 8 is a view in side elevation showing a sole being operated upon;

Fig. 9 is a plan view, partly in section, of the sole engaging instrumentalities;

Fig. 10 is a front elevation, partly in outline, showing a manual control for the slashing knife;

Fig. 11 is a side elevation of a portion of the control mechanism shown in Fig. 10; and

Fig. 12 is a plan view of the channel knife carrier.

As shown in Fig. 8, the work-engaging instrumentalities of the illustrated machine comprise a rotary work table 20 for supporting an insole S, a pair of channeling knives 24 and 26 (see also Figs. 7 and 9), a presser gage 28 associated with the channeling knife 24, a presser gage 30 associated with the channeling knife 26, a work retaining foot 32 (Figs. 1 and 2) for holding the work stationary during the cutting strokes of the channeling knives, an edge gage 34, and a pair of slashing knives 36 and 38 (see also Fig. 5). The channeling knife 24 makes an incision into the edge of the sole S to form a lip L and the channeling knife 26 makes an incision into the face of the sole S to form a lip L'. Although both knives are channeling knives, the knife 24 will hereinafter be called the edge knife to distinguish it from the knife 26 which will be termed the channeling knife. With the exception of the slashing knives 36 and 38, the members so far mentioned are similar to corresponding members of the machine disclosed in Letters Patent No. 1,023,801, above referred to, and are incorporated in a machine of generally similar construction.

The supporting structure of the illustrated machine comprises a head 40 (Figs. 1, 2 and 10) supported upon a column 42 which is adapted to rest upon the floor.

The channeling knives, the presser gages, and the slashing knives are all mounted, indirectly, in a swinging carrier 44 (Figs. 1 and 2) which is pivotally mounted upon a pair of cone bearings 46 to enable said knives and presser gages to swing to and fro in the direction in which the work is to be fed. The carrier 44 of the machine herein illustrated is similar to the carrier identified by the numeral 34 in Letters Patent 1,023,801, and it is similarly operated. The bearings 46 likewise are similar to the bearings 132 of the patented machine.

Referring to Figs. 8 and 9, it will be seen that the slashing knife 36 is arranged to slash that portion of the insole in which the lip L is to be formed, and that the slashing knife 38 is arranged to slash that portion of the insole in which the lip L' is to be formed. These knives, in order to avoid slashing into the between-substance, are spaced apart in a direction transverse to the line of feed by a distance greater than that which separates the tips of the knives 24 and 26. It will be noticed also (see Figs. 9 and 5) that the slashing knives 36 and 38 are staggered slightly in the direction of feed, the knife 36 being positioned slightly behind the presser gage 28 and the knife 38 slightly behind the presser gage 30. The slashing knives 36 and 38 are carried by the lower end of a bar 48, with provision for independent adjustment toward and from each other. The upper portion of the shank of the knife 36 is slotted to engage a complementary tongue formed on the lower end of the bar 48 for adjustment transverse to the line of work feed and is clamped in its adjusted position to the bar by a screw 50. The knife 38 has a similar tongue and groove connection with the bar 48 and is clamped thereto by a screw 52.

The bar 48, along its intermediate portion, is guided for heightwise movement in a guideway 49 (Fig. 12) formed in a carrier 213, later to be described, which swings with the carrier 44. On the upper end of the bar 48 is formed a block 54 (Fig. 5) which is secured by a clamping bolt 56 to a bracket 58. The bolt 56 extends horizontally through a hole in the bracket 58 and through a heightwise slot in the block 54 to provide for heightwise adjustment of the slashing knives. Threaded through the upper portion of the block 54 and extending down into the slot, above mentioned, is a screw 60 having a capstan head. The lower end of the screw 60 engages the bolt 56 and the head of the screw 60 engages the lower surface of a lug 62 extending from the bracket 58, the screw 60 thus being held against heightwise movement relative to the bracket 58. It is evident that when the clamping bolt 56 is loosened the height of the slashing knives relative to the bracket 58 may be adjusted by turning the screw 60.

The bracket 58 is pivotally connected by a pin 64 (Figs. 1 and 2) to the lower end of a link 66, the axis of the pin 64 being parallel to that of the pivotal support 46 to enable the bar 48 to swing with the carrier 44. The upper end of the link 66 is pivotally connected by a pin 68 to a cam lever 70 which in turn is fulcrumed upon a stud 72 fixed in the head 40. A torsion spring 74 urges the lever 70 in a counterclockwise direction as viewed in Figs. 1 and 2.

In order to determine the precise time, relative to the to-and-fro movements of the channeling knives, at which the slashing knives may thus be operated by the torsion spring 74, there is positioned directly beneath the midportion of the cam lever 70 a cyclic cam mechanism including a shaft 76 journaled in suitable bearings in the head 40 and having its axis parallel to that of the pivotal mounting 46. The shaft 76 is driven, by suitable gearing, in synchronism with the main shaft of the machine which actuates the swinging carrier 44 and the channeling knives. Mounted on the shaft 76 directly below the cam lever 70 is a snap cam 78 which is generally spiral in contour and which has an abrupt cam drop. Secured to and extending down from the cam lever 70 is a hardened steel wear block 80 adapted to ride upon the periphery of the cam 78. The cam 78 is so arranged that once in each cycle of its rotation its radial drop comes directly beneath the wear block 80 at the instant when the channeling knives have concluded their retracting or work-feeding step to the left and before they begin to swing back toward the right to effect a further channeling cut. At this instant, therefore, the cam lever 70 will be snapped down by the spring 74 to cause the slashing knives 36 and 38 to slash that portion of the insole in which the channel lips are to be formed, provided, however, that certain restraining means, shortly to be described, have previously released the lever to the action of the spring. When the lever snaps down it is brought to rest by contact of the wear block 80 with the cam face at the inner end of the radial drop in the cam and continued rotation of the cam will, therefore, raise the lever and the slashing knives to their initial operative positions.

The depth to which the slashing knives slash into the insole on descent of the cam lever 70 is controlled by adjustment of the screw 60. To avoid any chance of the slashing knives striking the work table by reason of excessive down-

ward adjustment, the bracket 58 is provided with a tail 81 (Figs. 1 and 5) which engages a safety stop in the form of a rubber pad 83 (see also Fig. 12) to absorb shock. The pad 83 is mounted in a cup 85 having a depending threaded shank 215 by which the cup is adjustably secured on the carrier 213.

With a view to allowing the slashing knives to descend to slash the insole only after chosen time intervals during which a series of work-feeding movements are imparted to the insole, the illustrated machine is provided with a cam lever restraining means which prevents descent of the lever 70 for each cycle of the machine and allows its descent only after the main shaft has made a predetermined number of revolutions and the channeling knives have effected a corresponding predetermined number of work feeding and channeling actions on the insole. This restraining means thus holds the slashing knives raised against the force of the spring 74. The restraining or holding means comprises an auxiliary cam shaft 82 (Figs. 1, 3 and 10) extending parallel to the cam shaft 76 and mounted in a stationary bracket 84 just below the stud 72. The shaft 82 is driven by suitable gearing, arranged at the rear of the machine, at one-twelfth the speed of the main shaft. More or less directly below the stud 72 are mounted upon the shaft 82 a pair of cam disks 86 and 88 arranged side by side along the shaft 82 and secured together for rotation as a unit. The cam disk 86 has formed upon it three equidistant cam-snugs 90 projecting radially from it and the cam disk 88 has two cam-snugs 92 arranged diametrically thereon and also extending radially therefrom. When the cam disks are driven, as will hereinafter be explained, each of the cam-snugs on a selected one of the cam disks serves to actuate a restraining latch 94 in such a manner as to release the cam lever 70 to the control of the snap cam 78.

Since the auxiliary cam shaft 82 is driven at one-twelfth the speed of the main shaft and the snap cam 78, it is evident that when the cam disk 86 is operative the descent of the cam lever 70 and the slashing knives will take place once in every four work-feeding movements of the channeling knives and their associated presser gages. Similarly, when the cam disk 88 is operative the slashing knives will be allowed to descend once for every six work-feeding movements.

The restraining latch 94 (Fig. 2), just referred to, comprises a horizontal bar extending widthwise of the machine above the auxiliary cam shaft 82. Formed on the left hand end of the latch 94 is an upstanding toe 96 (Fig. 1) which, when the latch is in operative position for restraining the cam lever 70, engages a notch 97 formed in the under surface of a secondary latch 98 pivotally mounted at its upper end upon a stationary pin 100 and having at its lower end a ledge 102 engageable with a notch formed in the rear portion of the wear block 80. A spring-pressed plunger 104 normally holds the secondary latch 98 against the side of the wear block 80 to maintain the secondary latch in its latching position. The left hand portion of the restraining latch 94 is supported upon a stationary rod 106 over which the latch slides freely. When the restraining latch 94 and the secondary latch 98 are in the positions shown in Fig. 1 the cam lever 70 is prevented from dropping with each revolution of the snap cam 78.

The restraining latch 94 is operated by a cam lever 108, the upper end of which is pivotally connected to the right hand end of the latch 94. The lever 108 extends downward at the right of the two cam disks 86 and 88 and is pivotally mounted just below said disks on a stationary bearing pin 110. Extending rearward from the lever 108 is a horizontal arm 112 (see also Fig. 4) parallel to and approximately in the same horizontal plane as the axis of the cam disks. Formed in the arm 112 is a dovetail guideway 114 and mounted in this guideway is a slide 116 (Fig. 1) having a cam-contact 118 projecting from it toward the peripheries of the cam disks and into the path of the cam-snugs on one or the other thereof. A tension spring 120 anchored at one end to a fixed portion of the head 40, and at its opposite end to the upper portion of the lever 108, urges the lever toward the cam disks as far as permitted by the contact of a face 122 on the lever with a cooperating face on the machine head.

It is evident that the spring 120 tends normally to hold the toe 96 of the restraining latch 94 in its cam-lever-restraining position. However, the cam-snugs on one or the other of the cam disks 86 and 88, by engagement with the cam-contact 118, rock the lever 108 toward the right and thus withdraw the ledge 102 of the secondary latch 98 from beneath the wear block 80 on the cam lever 70, thereby releasing the cam lever to the control of the cam 78. The abrupt drop in this cam almost immediately comes into position to permit the torsion spring 74 to urge the slashing knives down into the work, whereupon the continued rotation of the cam 78 raises the cam lever 70 high enough for it to be engaged by the ledge 102 of the secondary latch 98 which, by this time, will have been returned to its latching position. The lever 70 will thus be held in its raised position until the next cam-snug engages the cam-contact 118.

For operations along the sides of the insole, it is desirable that the cam lever 108 be subjected to the controlling action of the cam 86, which is provided with three snugs, thereby causing the slashing knives to perform a single operation for every fourth feeding movement of the insole. When the channeling is being performed around the toe end of the insole and the length of the feeding movements is reduced in order to facilitate the channeling operation, it is desirable that the cam lever 108 be controlled by the cam 88 which has two snugs, thereby providing a slashing action for every sixth feeding movement of the insole.

The illustrated machine is provided with means for automatically selecting the desired cam, such means being operated by an arm 109 (Figs. 1 and 2) which is similar to the arm numbered 156 in Letters Patent 1,023,801, above referred to. The arm 109 is connected to the cam-contact-supporting slide 116 by mechanism now to be described. Extending through a horizontal slot 123 (Figs. 2 and 4) formed in the base of the guideway 114 and engaging a heightwise slot formed in the slide 116 is a horizontal pin 124 the outer end portion of which is secured in the upper end of an arm 126 of a bell crank lever which is pivotally mounted upon a stationary stud 128. This bell crank lever has a forwardly and downwardly curved arm 130 the forward end of which is connected by a strong and rearwardly extending tension spring 132 to the rear end of a lever 134. This lever 134 is pivotally mounted

upon a stationary transverse pin 136 positioned about halfway between the forward end of the downwardly curved arm 130 and the stud 128, on the same level as the stud 128. The lever 134, as will presently be explained, is arranged to be swung about its pivot 136 to carry its rear end alternatively to positions above and below the stud 128. When the rear end of the lever 134 is above the stud 128 the spring 132 will pull upwardly and rearwardly upon the forward end of the arm 130 and will thus rock the bell crank lever 126, 130 in a clockwise direction as viewed in Fig. 4 and move the contact-supporting slide 116 into position to be engaged by the two-snug cam 88. Conversely, when the rear end of the lever 134 descends below the stud 128 (in which position it is shown in Fig. 4) the spring 132 will rock the bell crank lever in a counterclockwise direction and thus cause the slide 116 to be moved into a position for engagement with the three-snug cam 86. Secured to the lever 134 is a plate 133 having an arcuate slot which cooperates with a stationary pin 140 to limit the extent of the rocking movements of the lever 134. A similar arrangement, comprising a slotted arcuate portion 141 of the bell crank lever 126, 130 engaged by a stationary pin 142, limits the rocking movement of the bell crank lever 126, 130.

Operation of the lever 134 is effected through a link 144 the upper end of which is pivotally connected to a forward extension 148 of the lever 134. The lower end of the link 144 pivotally engages a trunnion pin 148 extending forward from a trunnion block 149 which in turn has a transverse pin 150 (Fig. 1) extending into and freely rotatable in an arm 152 of a bell crank lever. This bell crank lever is pivotally mounted for free rotation upon a shaft 154 which corresponds to the shaft numbered 158 in Letters Patent 1,023,801, above referred to, it being noted that the feed-length controlling arm 109 is secured upon the same shaft. A treadle rod 156 connected at its upper end to a crank 158 extending from the shaft 154 causes the arm 109 to descend when the treadle is depressed and such descent of the arm 109 causes the length of the work feeding steps to be reduced as has already been described in the Letters Patent just mentioned.

In the illustrated machine, the descent of the arm 109 is utilized also to rock the arm 152. For this purpose, the bell crank lever comprising the arm 152 has a downwardly extending arm 160 to which is pivotally connected, by a pin 162, the right hand end of a link 164 lying beneath and substantially parallel to the feed-length controlling arm 109. Extending forward from the arm 109 and rearward from the link 164 respectively are a pair of pins 166, one below the other. A more or less vertical link 168 has a pair of longitudinal slots 170 into which the pins 166 extend. A downwardly extending tension spring 172 connected at its upper end to the upper end of the slotted link 168 and at its lower end to the arm 109 acts normally to pull the link 168 down relatively to the arm 109 as far as permitted by the engagement of the upper end of the upper slot 170 with the upper pin 166. A second and somewhat weaker tension spring 174 connected at its upper end to the upper end of the slotted link 168 and at its lower end to the link 164 normally lifts the link 164 until the pin 166 extending from it meets the upper end of the lower slot in the link 168. Relative heightwise movement between

the arm 109 and the link 164 is thus permitted to take place in either direction.

Means for operating the link 164 is mounted upon a crank 176 which is like the crank numbered 144 in Letters Patent 1,023,801, above mentioned. This means comprises a bar 178 mounted in a guideway formed in the crank 176 to provide for heightwise adjustment, it being understood that as the crank rocks to perform its normal operative movements, the bar 178 will rock with it. The bar 178 is secured in adjusted position in its guideway by a screw 179. The upper end of the bar 178 projects above the crank 176 and lies close by the side of the link 164. Extending upward from the link 164 is an ear 180 presenting at its left hand side a flat face adapted to be engaged by the right hand face of a rearwardly extending block 182 on the upper end of the bar 178. When the arm 109 is drawn downward by the treadle to cause a reduction in the length of the work feeding movements, the link 164 moves downward with it and the upwardly extending ear 180 is lowered into the path of the block 182. If the under surface of the ear 180 should descend upon the upper end face of the block 182, the link 164 may yield upward and, as the block 182 moves toward the left, it permits the ear 180 to descend on the right hand side of the block 182. When the bar 178 next rocks toward the right the block 182 will engage the ear 180 and will thrust the link 164 toward the right, thus rocking the bell crank 160, 152 in a counterclockwise direction and causing the slide 116 to snap rearward away from engaging position with the three-snug cam 86 into a position for engagement with the two-snug cam 88.

Heightwise adjustment of the bar 178 in its guideway crank 176 will vary the precise stage in the downward feed-length reducing movement of the feed-length controlling arm 109 at which the bar actuates the link 164 to move the slide 116. For convenience, an indicating mark is placed upon the bar 178 and a corresponding series of scale markings are placed along one of the sides of its guideway to facilitate the setting of the bar to cause the slashing knives to operate on every sixth movement of the work when the desired reduction of the length of each feeding movement has been effected by depression of the treadle.

Formed upon the left hand end of the link 164 and considerably below the level of the ear 180 is an abutment lug 184. When the link 164 is in its lower position for the ear 180 to be engaged by the block 182, the lug 184 will lie below the path of movement of the block 182 and will not, therefore, be engaged by the block. However, when the treadle is allowed to rise to increase the length of the work feeding movements after the insole has been channeled around its toe portion, the lug 184 will move upward into the path of rocking movement of the block 182 and will be thrust toward the left upon the next swing of the bar 178 in that direction. The effect of such movement will be to shift the slide 116 back again into a position of engagement with the three-snug cam 86, whereupon the slashing knives will be operated once for every fourth work feeding movement of the channeling knives.

It is evident that various pairs of cam disks each having a desired number of cam snugs may be used in place of the disks 86 and 88. Since the cam disks rotate at one-twelfth the speed of the main shaft, the number of cam snugs on each 76 of the disks must be an integral factor of 12, i.e.,

2, 3, 4 or 6. For example, if one of the two cam disks should be provided with four cam snugs, then the slashing knives when operated by the cam would slash the work once for every third feeding movement. Such provision for varying the number of cam snugs and for adjusting the heightwise setting of the bar in the rocking crank renders the machine adaptable to a wide range of conditions in the stages at which the slashing knives become operative when the channeling progresses along the sides of the insole and around the toe thereof.

As has previously been stated, the cam disks 86 and 88 are mounted for free rotation upon the auxiliary cam shaft 82. These cam disks are arranged to be driven from the shaft 82 by means, presently to be described, which is automatically rendered inoperative when there is no work in the machine and the latter is running idly and which also may manually be rendered inoperative when the use of the slashing knives is not desired. To this end, the shaft 82 is provided with a radial flange 186 (Fig. 3) of greater radius than the cam disks and having secured upon it four short rectangular studs 188 (see also Figs. 1 and 10) equidistant from each other and extending parallel to the axis of the shaft 82, each stud constituting a driving member. The cam disks 86 and 88 are securely mounted on a sleeve 190 which is freely rotatable upon the shaft 82. The rear end of said sleeve is provided with a radial flange 192 of smaller diameter than the cam disks and spaced from the flange 186 by a spacing collar 194. This collar 194 and also the flange 192 are of small enough diameter to clear the four driving studs 188. The cam disks 86 and 88, the sleeve member 190, and the spacing collar 194 are secured together in fixed relation by a pin 196 which passes through aligned openings in the cam disks and the spacing collar and the flange of the sleeve. Threaded upon the forward end of the sleeve 190 is a knurled nut 198 which serves further to secure the cam disks on the sleeve. Portions of the flange 192 and the collar 194 are cut away to receive a pawl 200 which constitutes a driven member arranged to be engaged by any one of the driving studs 188. This pawl 200 is in the form of a bell crank and is pivotally mounted by means of a pin 202 upon the flange 192, its freedom for such pivotal movement being limited to a small angle by the engagement of the two arms of the pawl with adjacent faces in the recess in which the pawl is seated. The auxiliary cam shaft 82 is driven in a clockwise direction as seen from the front of the machine and one of the arms of the pawl 200 extending to the right of the pivot 202 carries a lug 204 which is normally thrust outward by a spring-pressed plunger 206 into the path of the driving studs 188. The plunger 206 is housed in the flange 192 and operates against the adjacent edge of the arm of the pawl 200. So long as the lug 204 is thrust outward by the plunger 206, one of the driving studs 188 will remain in driving engagement with the lug 204 and thus cause the sleeve 190 and the cam disks 86 and 88 to rotate with the auxiliary shaft 82.

A second arm 208 of the pawl 200 extends more or less radially outward just beyond the periphery of the flange 192 and may be engaged by a slashing-knife cut-out lever 210 mounted upon a shaft 209 journaled in suitable bearings in the stationary head 40. The lever 210 is arranged to abut against the left hand edge of the outer

end portion of said arm to immediately swing the pawl 200 in a direction to move the lug 204 inward out of engagement with the stud 188, thereby disengaging the drive of the cam disks. During continued rotation of the shaft 82, the studs 188 pass idly over the lug 204 and across the other arm of the pawl 200 and the cut-out lever 210.

In order that the pawl 200 shall thus stop the rotation of the cam disks 86 and 88 with the slashing knives remaining in their raised inoperative positions when the machine is running idly and there is no insole being operated upon, means are provided for enabling the channel knife presser gage 30 to control the pawl 200. To this end the gage 30 is provided with an upwardly extending stem 212 (Fig. 6) guided for limited heightwise movement in a guideway 211 (Fig. 12) formed in the carrier 213. This carrier 213 replaces the channel knife carrier 68 of the machine disclosed in Letters Patent No. 1,023,801, and, as has already been mentioned, it has formed in it a guideway 43 for the bar 44. The carrier 213 supports the channel knife 24 and is mounted on a slide provided in the swinging carrier 44, said slide corresponding to the channel knife slide numbered 36 in said Letters Patent. Threaded into the upper end of the stem 212 is a vertical stud 214 having a head 216 and a collar 218 below the head. The adjacent portion of the carrier 213 in which the stem 212 is guided for heightwise movement has formed upon it a flange 220 which extends into the space between the head 216 and the collar 218 and it has also a lower flange 222 which supports the collar 218 and, therefore, the presser gage when the machine is at rest. The lower face of the upper flange 220 and the upper face of the lower flange 222 are spaced far enough apart to provide for a relative heightwise movement of the stem 212 to the extent of about one-sixteenth of an inch. When an insole is fed across the work support 20, which is yieldingly held up in operating position by a spring in the usual manner, the insole passes under the presser gage 30 and thrusts the gage upwardly until the upper face of the collar 218 engages the upper flange 220 and this slight vertical movement relative to the carrier 213 is utilized to cause the pawl 200 to be moved into operative position with respect to its driving member. To this end, the upper portion of the carrier 44 has a pair of laterally extending ears 224 which carry a pin 226 positioned approximately on the level of the upper face of the flange 220. A bell crank lever freely mounted on the pin 226 has a short horizontally extending arm 228 which bears down upon the head 216. A spring-pressed plunger 230 (Fig. 1) housed in the carrier 213 thrusts outward against a lug 232 which extends downward from said bell crank lever and tends, therefore, to thrust the gage 30 down. The bell crank lever has a relatively long upwardly extending arm 234 connected by a substantially horizontal link 236 to a short downwardly extending crank 238 on the shaft 209, above mentioned. It should be observed that the link 236 passes approximately through the axis of the pivotal mounting 46 of the carrier 44 and that, therefore, the rocking movements of the carrier 44 about said axis will not appreciably shift the link 236 longitudinally.

When the machine is at rest or is running idly, the pawl 200 will be held out of engagement with the driving studs 188 by the cut-out lever 210 but the rising of the presser gauge 30, which occurs

on insertion of the work in the machine, will rock the cut-out lever in a clockwise direction as seen from the front of the machine and move it out of engagement with the arm 208 of the pawl 200, thereby releasing the pawl to the action of the spring plunger 206 which moves the pawl into operative relation to the driving studs. The cam disks 86 and 88 thus become coupled to the auxiliary cam shaft 82 and rotate therewith.

A second and similar cut-out lever 242 (Fig. 10) is freely mounted on the shaft 209 by the side of the lever 210. Extending from the lever 242 is a handle 244 for enabling the operator to engage the lever 242 with the pawl arm 208 to stop the drive of the cams 86 and 88, notwithstanding the fact that the pawl 200 has been released by the cut-out lever 210 on the rising of the presser gage 30.

For more convenient operation of the cut-out lever 242, a crank arm 246 extends from the hub of the handle 244. Pivots connected to the outer end of the arm 246 is the lower end of a link 248, the upper end of which is connected to the left hand end of a substantially horizontal lever 250 pivotally mounted upon a stationary pin 252. The right hand end of the lever 250 is pivotally connected to the upper end of a rod 256 the lower end of which is pivotally connected to an arm 258 of a bell crank (see Fig. 11). This bell crank, which is pivotally mounted on a pin 260 secured in a stationary bracket 262, has a short upwardly extending arm 264 the upper portion of which is in the form of a thumb piece 266 having a smooth flat surface for convenient operation by the pressure of the operator's thumb.

When the operator draws the thumb piece 266 forward and thereby rocks the bell crank arm 258 up, he causes the rod 256 to rock the lever 250 in a counterclockwise direction and thereby exert a downward thrust on the link 248 to rock the cut-out lever 242 into engagement with the arm 208 of the pawl 200. The operation of the slashing knives is then stopped until the operator presses rearward upon the thumb piece to disengage the cut-out lever 242.

When the rotation of the cams 86 and 88 has been stopped by either of the cut-out levers 210 or 242, these cams will be held against retrograde movement by a pawl 268 (Figs 1 and 10) which is engageable with a notch in the periphery of the flange 192. The pawl 268 extends from a sleeve 270 which is freely rotatable on a stationary pin mounted in the machine head 40. The pawl 268 is urged toward engaging position by a tension spring 274 attached at one end to the head 40 and at its other end to a crank arm 272 extending from the sleeve 270.

Having described my invention, what I claim as new and desire to secure by Letters Patent of the United States is:

1. A machine for operating upon soles comprising a knife arranged to make cuts in a sole, at least two mechanisms each of which is constructed and arranged to cause said knife to be operated periodically in timed relation to the operating cycle of the machine at a ratio between the operating cycles of the machine and the operations of said knife which is different from the operating ratio of the other mechanism, and means for selectively rendering operative either of said mechanisms to cause the knife to be operated at a desired ratio.

2. A machine for operating upon soles comprising a knife arranged to make cuts in a sole, at least two driven cams, mechanism adapted to be

controlled by either of said cams for operating said knife, said cams each being constructed and arranged to control said mechanism to cause the operations of said knife to take place at a ratio between the operating cycles of the machine and the operations of the knife which is different from the operating ratio of the other cam, and means for selectively engaging said operating mechanism with either of said cams to cause the knife to be operated at a desired ratio.

3. A channeling machine for operating upon soles comprising a channeling knife, a main shaft, mechanism driven by said main shaft for oscillating said channeling knife to cause it to make cutting and feeding strokes, a secondary shaft geared to the main shaft, a plurality of cams of different characteristics driven by said secondary shaft, a cam follower selectively engageable with said cams, a slashing knife arranged to make cuts in the area operated upon by the channeling knife, mechanism controlled by said cam follower for operating the slashing knife periodically in timed relation to the oscillations of the channeling knife, and means for selectively engaging said cam follower with any one of said cams to cause the slashing knife to be operated periodically, the ratio between the operations of the slashing knife and the oscillations of the channeling knife being dependent upon the cam selected.

4. A machine for operating on soles comprising a knife arranged to make cuts in a sole, a spring acting upon said knife to cause the knife to make a cutting stroke, a cyclic cam mechanism adapted once in each of its cycles to raise the knife against the force of said spring, means independent of said cam mechanism for holding the knife raised against the force of said spring during a plurality of cycles of the cam mechanism, and means operable periodically to release the knife from said holding means after a plurality of cycles of the cam mechanism have taken place and thereby to enable the spring to operate the knife, subject to the control of said cam mechanism.

5. A channeling machine comprising a knife for forming a channel lip on a sole, a support for the sole, a presser gage engageable with the upper surface of the sole and associated with said channeling knife to control the heightwise position of the knife, a knife for cutting slashes in a portion of the sole in which a channel lip is to be formed, means for operating the slashing knife periodically, and means controlled by said presser gage for stopping the operation of said operating means when the sole passes out from under said presser gage.

6. A machine for operating upon soles comprising a support for a sole, a knife for cutting slashes in a portion of the sole in which a channel lip is to be formed, means for operating said slashing knife periodically, means responsive to the presence of a sole on the support for rendering the operating means operative only while there is a sole on the support, and manually actuated means for stopping the operation of said operating means notwithstanding the presence of a sole on the support.

7. A channeling machine comprising a knife for forming a channel lip on a sole, a support for the sole, means for oscillating said knife to cause it to make cutting and feeding strokes, a presser gage engageable with the upper surface of the sole and associated with said channeling knife to control the heightwise position of the

13

knife, a knife for cutting slashes in a portion of the sole in which the channel lip is to be formed, means for operating said slashing knife periodically in timed relation to the cutting and feeding strokes of the channeling knife, means for varying the period of operation of said slashing knife relative to the number of strokes of the channeling knife, and means controlled by said presser gage for rendering the slashing knife operating means inoperative except when the presser gage engages a sole on the work support.

LAWRENCE MAWBEY.
